(57) **CLAIM**

We claim the ornamental design for a plunger and finger grip for a hypodermic syringe, as shown and described.

DESCRIPTION

FIG. 1 is a perspective view of a hypodermic syringe; FIG. 2 is a front elevation view of the hypodermic syringe of FIG. 1;

FIG. 3 is a side elevation view of the hypodermic syringe of FIG. 1;

FIG. 4 is a bottom perspective view of the hypodermic syringe of FIG. 1;

FIG. 5 is a perspective view of an alternate configuration of the hypodermic syringe of FIG. 1; and,

FIG. 6 is a perspective view of another alternate configuration of the hypodermic syringe of FIG. 1.

The features shown in broken lines depict environmental subject matter only and form no part of the claimed design.
